Attorney

UNITED STATES PATENT OFFICE

JOHN P. NISSEN, JR., OF PHILADELPHIA, PENNSYLVANIA

MARKING IMPLEMENT

Application filed October 18, 1927. Serial No. 226,998.

The object of the present invention is to provide a marking implement in which the marking material of viscous character is kept in a container from which it may be expelled, and from which air is at all times excluded, the elements being such that they can be cheaply manufactured, so that when the material is entirely used, the implement can be discarded.

10 The preferred embodiment of the invention is illustrated in the accompanying drawings, wherein:—

Figure 1 is a perspective view of the implement,

15 Figure 2 is a longitudinal sectional view through the nipple end of the same,

Figure 3 is a perspective view of the spring supporting saddle,

20 Figure 4 is a top plan view of said saddle with the spring mounted thereon.

In the embodiment disclosed a collapsible non-elastic tubular body 5 is provided that constitutes a container for the viscous marking material, and also forms a permanently 25 collapsible handle for manipulating the implement and expelling the contents of the body. This body is provided at one end with a conical end wall 6, which carries as a permanent and preferably integral part there- 30 of, an outstanding externally threaded nipple 7 having an opening 8, through which the contents are discharged. The other end of the body 5 is preferably crimped or otherwise closed, as shown at 9.

35 Screwed on the nipple 7 is an internally threaded cap 10, the outer end of which is tapered as shown at 11, and is provided with a central discharge orifice 12, behind which is formed a valve seat 13. In the outer end 40 of the nipple and normally bearing against the seat 13 so as to close the orifice 12 is a ball 14 that thus constitutes a closure valve and a marking element.

An open saddle is located within the cap 45 and is preferably formed of wire bent into a ring 15 that surrounds the opening 8 and rests on the outer end of the nipple 7. This wire is further bent into an inwardly extending loop or yoke 16 that enters the nipple 7 and terminates in a central outwardly ex-

tending holding stem 17 that terminates short of the ball 14. On the stem 17 is a coiled spring 18 that rests against the inner end of the loop 16 and bears against the inner side of the ball 14.

As already indicated, the body 5 is filled 55 with a viscous marking material of the consistency of thick paint, and it completely fills the body and cap.

In using the implement, the operator inverts it, grasps the body as a handle and moves the ball 14 over the fabric or other material to be marked. This obviously rotates the ball and moves it inwardly against the action of the spring, so that the pressure 60 of the hand will expel the contents through the orifice 12 at the desired rate to properly mark. The body, being non-elastic, is gradually compressed and retains its compressed condition so that no air will enter to harden 65 the contents and the ball constitutes a seal that will prevent the expulsion of the material except when pressed inwardly in use. Because of the simplicity of the structure, it is not intended to be refilled, but is discarded 70 when the contents are completely exhausted.

75 From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages 80 of the invention.

85 What I claim, is:

1. A marking implement comprising a collapsible, substantially non-elastic, tubular body constituting a container for a viscous marking material and a permanently collapsible handle for manipulating the implement and expelling the contents, a discharge member on one end of the body through which said marking material finds egress, a combined marker and closure for the member 90 movably mounted therein and projecting therefrom, and means for yieldingly holding the marker and closure in its projected and closing position.

2. A marking implement comprising a collapsible, substantially non-elastic, tubular body constituting a container for a viscous marking material and a permanently collapsible handle for manipulating the implement and expelling the contents, a discharge member on one end of the body through which said marking material finds egress, a combined marker and closure ball for the member movably mounted therein and projecting therefrom, and a spring operating against the inner side of the ball for yieldingly holding it in its projected and closing position.
3. A marking implement comprising a collapsible, substantially non-elastic, tubular body constituting a container for a viscous marking material and a permanently collapsible handle for manipulating the implement and expelling the contents by being permanently collapsed, a nipple permanent with and projecting from one end of the body, a cap fitted on the nipple and having a discharge orifice in its outer end, a ball in the cap and normally closing the orifice, an open saddle seated on the outer end of the nipple and having a spring support extending inwardly into the nipple and an outwardly-extending spring holding stem, and a coiled spring seated on the support, surrounding the stem, and bearing against the ball.
4. A marking implement comprising a collapsible, substantially non-elastic, tubular body constituting a container for a viscous marking material and a permanently collapsible handle for manipulating the implement and expelling the contents by its permanent collapse, an externally threaded nipple on one end of the body, an internally threaded cap screwed on the nipple and having a tapered end provided with an exit orifice, a ball in the tapered end controlling the orifice, a ring mounted on the outer end of the nipple with the cap and carrying an inwardly disposed loop having an outstanding stem, and a coiled spring on the stem supported by the loop and bearing against the inner side of the ball.
5. A marking implement comprising a collapsible, substantially non-elastic, tubular handle body having a front end wall and a non-collapsible discharge nipple projecting from the end wall and of less diameter than the tubular body, a cap mounted on the nipple and having a discharge orifice, and a marking device yieldingly mounted in the cap and on the nipple and projecting through the orifice.
6. As an article of manufacture, a non-refillable implement for marking, comprising a collapsible substantially non-elastic tubular body having a projecting non-collapsible nipple on one end of less diameter than the body and provided with an egress opening, a body of viscous marking material in the body holding said body distended and sufficiently rigid to permit its being held as a handle in operating the implement when marking goods, said marking material finding egress through the nipple when the body is compressed, and a combined marker and closure for the nipple opening, said marker and closure being yieldingly mounted on the end of the nipple and operating to transfer the expressed viscous marking material to the goods being marked when the body is manipulated and pressed, and acting to prevent the egress of the material when the body is not in use.
- In testimony whereof, I affix my signature. 80
